(57) **CLAIM**

The ornamental design for a reclining chair, as shown and described.

DESCRIPTION

FIG. 1 is a left-side elevation of a reclining chair of my invention.

FIG. 2 is a left-side elevation of the chair shown in FIG. 1, shown in a reclining position.

FIG. 3 is a left-side elevation of the chair shown in FIG. 1, shown in another reclining position.

FIG. 4 is a front elevation of the chair shown in FIG. 1.

FIG. 5 is a right-side elevation of the chair shown in FIG. 1.

FIG. 6 is a top plan view of the chair shown in FIG. 1.

FIG. 7 is a bottom plan view of the chair shown in FIG. 1.

FIG. 8 is an isometric view of the chair of FIGS. 1-6, viewed from the right front of the chair.

FIG. 9 is an isometric view of the chair of FIGS. 1-8, viewed from the left back bottom of the chair; and,

FIG. 10 is a rear elevation of the chair shown in FIG. 1.
